UNITED STATES PATENT OFFICE

103,230

DESIGN FOR A LABEL BLANK

Arthur William Hanley, Tampa, Fla.

Application November 16, 1935, Serial No. 59,618

Term of patent 14 years

To all whom it may concern:

Be it known that I, Arthur W. Hanley, a citizen of the United States, residing at 2410 Watrous Avenue, in the city of Tampa, county of Hillsborough and State of Florida, have invented a new, original, and ornamental Design for a Label Blank, of which the following is a specification, reference being had to the accompanying drawing forming a part hereof.

The drawing is a face view of a label blank, having no appreciable thickness, embodying the design.

I claim:

The ornamental design for a label blank, as shown and described.

ARTHUR WILLIAM HANLEY.
